PNEUMATIC THREAD HOLDER FOR WEFT
REPLENISHING LOOMS

Richard G. Turner, Worcester, Mass., assignor to
Crompton & Knowles Loom Works, Worcester,
Mass., a corporation of Massachusetts

Application October 9, 1946, Serial No. 702,197

13 Claims. (Cl. 139—247)

1

This invention relates to improvements in weft replenishing looms and it is the general object of the invention to provide improved pneumatic thread holder means for the weft ends extending from a reserve bobbin magazine.

Heretofore I have proposed the use of pneumatic thread holders for the purpose of tensioning the weft ends of reserve bobbins and also removing the weft ends after they have been cut at the selvage subsequent to replenishing operations, and have also proposed a thread accumulator or collector into which the cut threads are drawn to prevent them from being whipped into the shed. In these earlier proposals a screen or the like has been introduced between an air pump and the thread collector to prevent the threads from being drawn into the pump and also permit the subatmospheric pressures of the pump to be transmitted to the thread collector. In such structures the weft ends collect at and tend to clog the screen resulting in a material reduction in the pneumatic pressure tending to draw the threads into the accumulator. It is an important object of my present invention to provide the interior of the accumulator with an elongated porous tube presenting a relatively large surface and connect its interior to the air pump. By this arrangement the subatmospheric pressures are created within the thread collector over a large area and there is little or no tendency for the threads to collect at any one point and clog the air path.

The weft ends from the reserve bobbins generally extend downwardly along downwardly inclined paths and pass through an intake mouth into a hollow compartment connected pneumatically to the interior of the thread collector. When a bobbin is transferred it is desirable that its thread become disassociated from the weft ends of the bobbins remaining in the magazine so that when cut it may be quickly drawn into the thread collector. It is another object of my present invention to provide the thread holder with a baffle or guide wall along which the weft ends extend and form the thread holder with an air inlet so positioned that the weft ends will be blown upwardly along the wall for the purpose of disturbing them to assist disengagement of a cut weft end from the bundle of weft ends still connected to the untransferred bobbins.

It is a further object of the invention to provide a thread collector which depends from the thread holder and provide the latter with a thread opening located preferably behind a line leading from the intake mouth to the aforesaid baffle or guide

2

wall. When the opening is thus placed the weft ends bend around the guide wall and then hang down through the opening into the collector.

In order that the bundle of weft ends within the accumulator may be effectively prevented from reentering the thread holder proper, it is a further object of the invention to provide prongs, tines or the like which become embedded in the mass of hanging threads to prevent upward movement thereof but offer no appreciable resistance to downward movement of the mass of threads into the collector.

With these and other objects in view which will appear as the description proceeds, my invention resides in the combination and arrangement of parts hereinafter described and set forth.

In the accompanying drawings, wherein a convenient embodiment of my invention is set forth.

Fig. 1 is a side elevation of part of a loom having my invention applied thereto,

Fig. 2 is an enlarged plan view looking in the direction of arrow 2, Fig. 1,

Fig. 3 is a side elevation looking in the direction of arrow 3, Fig. 2,

Fig. 4 is a detail horizontal section on line 4—4 of Fig. 3,

Fig. 5 is a vertical section on line 5—5 of Fig. 4.

Fig. 6 is a detailed side elevation taken in the direction of arrow 6, Fig. 5, showing that part of the thread holder which faces the reserve bobbin magazine,

Fig. 7 is a vertical section on line 7—7 of Fig. 4,

Fig. 8 is a horizontal section on line 8—8 of Fig. 3, and

Fig. 9 is an enlarged detailed vertical section on line 9—9 of Fig. 8 through the lower part of the thread accumulator and porous tube.

Referring particularly to Fig. 1 a loom frame 10 is provided with a crank shaft 11 to reciprocate a lay 12 on which the shuttle 13 travels. A lever 14 appropriately pivoted on the loom is reciprocated by a rod 15 connected to the lay and the upper end of the lever is attached to a piston rod 16 which drives a piston 17 of an air pump 18 fixed to the loom. A pipe or hose 19 leads forwardly from the pump, and the latter has appropriate valve mechanism not shown so that upon rearward movement of the lay subatmospheric pressures are created within hose 19, but the latter is sealed from the pump during forward movements of the lay.

The magazine M is provided with a plurality of reserve bobbins 20 from which weft ends 21 extend to a thread holder designated generally 55 at H. At the time of a weft replenishing opera-

tion a transfrerer arm 22 is depressed to move a bobbin from the magazine into the shuttle, and at this time the weft end of the transferred bobbin moves downwardly from the other weft ends and is subsequently cut at the selvage. When cut this weft end is drawn into the thread holder.

Except as pointed out hereinafter with respect to holder H the matter thus far described is of common construction and may be as set forth in my prior Patent No. 2,199,353.

In carrying my present invention into effect I provide a floor supported upright 25 to the upper end of which is secured a stand 26 bolted as at 27 to the thread holder H. The pipe 19 extends downwardly along the upper part of the upright and is secured thereto by clips 28.

The thread holder is formed as shown more particularly in Figs. 4-7 and includes a hollow casting 30 having an opening or intake mouth 31 facing the magazine. A plate 32 is held in vertically adjusted position on the thread holder by adjusting nuts 33 which permit a variation in the height of the mouth. When fine wefts are being woven the mouth can be narrow, but when coarse wefts are used the plate can be raised to widen the mouth.

Casting 30 is formed with a thread compartment 35 sealed from the atmosphere at the top thereof by a cover 36 preferably transparent and hinged to the casting as at 37. The thread compartment has a front wall 38 and a floor 39. A thread guiding flange 40 extends downwardly and forwardly from the floor, and a threading slot 41 is cut vertically in the floor 39 behind wall 38 and at the upper rear end of the flange 40. This thread slot communicates at its inner end with the intake mouth 31 as at 42, and at its outer end is extended upwardly to form a slot 43 in the side wall 44 of casting 30. A thread opening 45 at the upper end of slot 43 is adjacent to a vertical wall projecting from casting 30 and extending downwardly as at 47 from floor 39 behind thread slot 41.

When new bobbins are placed in the magazine their weft ends are drawn outwardly from the reserve bobbins and moved upwardly between flange 40 and wall 47 and then vertically through the thread slot 41. The ends of these threads adjacent the magazine pass through the opening 42 into the intake mouth 31, while the ends thereof remote from the magazine rise in the slot 43 and enter opening 45 and are then draped over the back of guide or wall. From this position the outer ends of the threads are quickly drawn through the opening 45 into compartment 35 by suction.

Casting 30 is formed with a substantially vertical guide wall 50 immediately behind slot 41 and extending from the floor 39 to the cover 36. As the weft ends enter the intake mouth 31 they will be spread out as suggested in Fig. 4 and converge along the vertical edge of wall 50, the latter becoming a guide to produce bends in the weft ends as they lead rearwardly.

Certain features of the thread holder already described are similar to the structure set forth in my copending application Serial No. 626,462, filed November 3, 1945, now Patent No. 2,427,538. Such novel matter as is common to this disclosure and that application is claimed in the latter.

The outer rear part of floor 39 has a vertical opening 55 therein providing an air and thread passageway from compartment 35. Secured to

the floor and projecting down along that edge of opening 55 adjacent to the guide wall 50 are thread ensnaring tines or prongs 56. The casting 30 is formed with a disk-like base 57 shown in Fig. 4 from which extends a flat horizontal arm 58 supported by stand 26.

The thread collector or accumulator comprises a hollow cylinder 60 made preferably of transparent plastic material the upper end of which is held tightly against the under surface of the circular base 57 by bolts 61 extending along and outside of the cylinder 60. Wing nuts 62 engage the top of base 57 to support the bolts, and the latter extend downwardly through open slots 63 in a ring 64 to hold the latter tightly against the bottom of the cylinder 60. When the nuts 62 are tight the ring or bottom 64 is raised against the cylinder and lifts the latter against the base 57. Loosening of nuts 62 and a partial rotation of ring 64 permits the latter and cylinder 60 to be removed.

A disk 65 is fitted to the ring 64 as shown more particularly in Fig. 9 and is held in position by clips or the like 66 mounted on ring 64. Clips 66 are movable to a position where they will release the disk 65 from the ring or bottom 64. A pneumatic fitting 70 is secured to the disk 65 by screws 71 and communicates with the previously described pipe 19. Disk 65 has a series of apertures 72 which open upwardly from fitting 70.

Disk 65 is recessed as at 75 and has set therein a tubular member 76 extending upwardly from the disk and having its upper end closed by a cover 77. A tie rod 78 has a head 79 on the under side of the disk 65 and has a nut 80 on the upper end thereof by which the cover 77 can be drawn down tightly against the top of the tube 76. Bolt 78 provides the means by which the tube 76 is held in fixed position seated in recess 75. The tube 76 has porous walls through which air can pass when subatmospheric pressures are created within the tube. The latter extends substantially parallel to and coaxial with cylinder 60 and presents a relatively large surface exposed to the interior of the thread collector. The length of tube 76 is determined by the amount of air which it is desired to have moving through the tube under any given atmospheric pressure.

It is believed that the operation of the thread holder and accumulator will be understood from the foregoing description. When the loom is running the air pump creates subatmospheric pressures on the inside of the porous tube 76 during backward strokes of the lay. This pressure is communicated to the interior of cylinder 60 through the porous walls of the tube, and thence through opening 55 to compartment 35, intake mouth 31, slots 41 and 43, and opening 45. During loom operation a small column of air rises periodically through the thread slot 41 in the direction of arrows a, Fig. 5, and blows the weft ends up along the thread guide wall 50. This movement of the weft ends along the guide wall facilitates release of the weft end of a transferred bobbin when the end is cut at the cloth selvage. Such cut weft end is thus subjected to an upward pneumatic force in addition to the force exerted at mouth 31, and these two forces quickly draw the thread into compartment 35 and thence to cylinder 60. Because of the size of tube 76 subatmospheric pressures within it are communicated to the interior of the cylinder 60 over a large area and there is little or no

tendency for the threads to bunch together in one position where they might clog an air stream as has been possible in thread accumulators as heretofore made.

From time to time it may be desirable to remove the accumulated weft ends from the interior to the cylinder 60, and to facilitate this operation I provide a door D hinged at 81 to a casting 82 having a part-cylindrical flange 83 held to the cylinder 60 by screws 84. That part of the cylinder adjacent to the casting 82 is cut away to communicate with a passageway 85 on the interior of the casting 82. The door D is hung so that it closes naturally by gravity, but suction from within the cylinder 60 also helps to hold it tightly closed. When it is desired to remove threads from within cylinder 60 the door D is lifted and the threads are removed through the passageway 85. It is found in actual practice that the bundle of weft ends hanging from floor 39 does not collect around tube 76 and can be readily removed.

If it should be desired to remove the tube 76 for a cleaning operation the clips 66 may be moved as already suggested and the fitting 70, disk 65 and the tube 76 removed, after which nut 60 is released from rod 78 and the cover 77 is removed to release the tube 76.

From the foregoing it will be seen that I have provided an improved form of pneumatic thread holder employing a relatively large cylinder 60 comprising a closed thread compartment, accumulator or collector within which is located a hollow porous member or tube communicating with a pneumatic means for creating subatmospheric pressures, such as the pump 10. The tube 76 has a large area and by reason of the porosity of its walls allows air to pass from the interior of the cylinder 60 to the pump to create subatmospheric pressures within the chamber or thread compartment 35. The method of mounting the cylinder 60 assures that it is air-tight except for the intake mouth 31, thread slots 41 and 43, and inlet 45. It will also be seen that the tube 76 is supported by a ring or bottom 64 which in effect is a base for the cylinder 60 and that although the tube 76 is normally in fixed position with respect to the cylinder it can be removed for cleaning purposes. The ring and disk 65 together constitute a closure for the bottom of cylinder 60. Furthermore, the prongs or tines 56 depending from that edge of opening 55 adjacent to wall 50 insure retention of the bundle of weft threads within the cylinder 60 after they have passed through the opening 55. Also, the thread slot 41 is so disposed with respect to the guide wall 50 that the weft ends are subjected to an upward force along said wall, and a thread cut at the selvage and extending into the intake mouth 31 will be blown upwardly as well as inwardly into the thread compartment 35.

The prongs depending from the floor of the thread holder into the thread accumulator or collector for engagement with the weft ends, although shown herein, are not claimed in this present application, but are the subject matter of a continuation in part application Serial No. 784,791, filed by me on November 8, 1947.

Having thus described my invention it will be seen that changes and modifications may be made therein by those skilled in the art without departing from the spirit and scope of the invention and I do not wish to be limited to the details herein disclosed, but what I claim is:

1. In a pneumatic thread holder having an in-

take mouth for the weft ends extending from reserve bobbins in a loom provided with pneumatic means to create subatmospheric pressures, hollow means communicating pneumatically with said mouth, a thread accumulator under said hollow means pneumatically connected to the latter by means of an opening in said hollow means and also connected pneumatically to said pneumatic means, a thread guide within the hollow means having a substantially vertical thread engaging edge intermediate the mouth and opening along which the weft ends extend, said hollow means having a thread slot extending upwardly from the lower part thereof and causing a draft of air to be directed upwardly against said weft ends.

2. In a pneumatic thread holder having an intake mouth for the weft ends extending from reserve bobbins in a loom provided with pneumatic means to create subatmospheric pressures, hollow means communicating pneumatically with said mouth and having a floor in which a thread receiving opening is formed, a hollow thread accumulator depending from the hollow means communicating pneumatically with the interior of said hollow means through said opening and connected pneumatically with said pneumatic means, and a thread guide within said hollow means having a vertical edge intermediate the mouth and opening forward of the latter and along which the weft ends extend when leading from the mouth to the opening, said floor having a substantially vertical thread slot therein forward of said vertical edge through which air is drawn upwardly against the weft ends to lift them from the floor.

3. In a pneumatic thread holder for the weft ends of a weft replenishing loom, said holder comprising a hollow body containing a thread compartment in which subatmospheric pressures can be created, said holder having a thread intake mouth and a thread aperture spaced from the mouth and having also a thread slot connecting said mouth and aperture, and a thread guide on said holder behind said aperture and over and behind which can hang the weft ends which extend through the mouth and aperture to be out of the path of weft ends which are inserted into the thread slot from a position in front of the guide.

4. In thread control mechanism for the weft ends of a weft replenishing loom, a thread holder comprising a hollow body having a floor and formed with a thread compartment above the floor, said holder having an intake mouth to receive the weft ends, a hollow thread collector depending from said floor, the latter having an opening therein pneumatically connecting said thread compartment with the interior of the thread collector, pneumatic means by which subatmospheric pressures can be created within the thread collector, and detachable means deriving support from said floor to support said pneumatic means and thread collector in position under said floor.

5. In pneumatic thread control mechanism for the weft ends of a weft replenishing loom, means providing a hollow thread compartment to receive the weft ends, a floor comprising part of said means, a hollow thread collector under the floor, support means under the thread collector, pneumatic means within the thread collector to create subatmospheric pressures therein, said floor having an opening therein pneumatically connecting said compartment with the interior

of said thread collector, means connecting said support means to the floor, and detachable means connecting said pneumatic means to the support means.

6. In a thread collector for the pneumatic thread control means for a weft replenishing loom, said thread collector comprising a hollow body having an opening therein, detachable closure means for said opening normally closing the latter, a tube of porous material extending into said hollow body, and means detachably supporting said porous tube on said closure means, said porous tube effective when subatmospheric pressures are created therein to create subatmospheric pressures within said hollow body.

7. In a thread collector for the weft ends of a weft replenishing loom, a hollow body to receive the weft ends having an open end, closure means for said open end of said hollow body including two parts, one of said parts being fitted to the hollow body and the other part being fitted to said one part, detachable means holding said parts together, and hollow pneumatic means supported by said other part, said pneumatic means being removable with said other part when the latter is detached from said one part.

8. In a thread collector for a pneumatic weft end holder of a weft replenishing loom, a hollow thread collecting member for the weft ends, closure means to seal the interior of the hollow member from the atmosphere and including two parts one of which fits said hollow member and the other of which fits said one part, a hollow member within said thread collecting member having porous walls, detachable means normally securing said hollow porous member to said other part, detachable means normally connecting said parts together, and detachable means normally holding the closure means suspended from the weft end holder, said porous member being removable from said other part when the latter is detached from said one part.

9. In a thread holder for the weft ends of a weft replenishing loom, said holder comprising a hollow member having a thread compartment therein and having also a thread slot therein on the under side thereof connecting the compartment to the atmosphere, a thread guide wall extending substantially vertically downwardly from one side of said thread slot, and a second thread guide wall extending downwardly from the opposite side of said thread slot and obliquely with respect to said first named wall, said member having a thread receiving mouth on one side of said compartment communicating with said thread slot and having a thread aperture on the other side of said compartment also communicating with said thread slot, said walls cooperating to guide weft ends which are raised from under said thread holder toward said thread slot for movement therethrough and into said mouth and aperture.

10. In a thread holder for the weft ends of a weft replenishing loom, said holder comprising a hollow member having a thread compartment therein and having also a thread slot therein on the under side thereof connecting the compartment to the atmosphere, a thread guide wall

extending substantially vertically downwardly from one side of said thread slot, a second thread guide wall extending downwardly from the opposite side of said thread slot and obliquely with respect to said first named wall, said member having a thread receiving mouth on one side of said compartment communicating with said thread slot and a thread aperture on another side of said compartment also communicating with said thread slot, said walls cooperating to guide weft ends which are raised from under said thread holder toward said thread slot for movement therethrough and into said mouth and aperture, and an extension on the first named wall located behind said aperture over and behind which weft ends may hang to be out of the path of other weft ends which are moved upwardly between said walls and through said thread slot.

20 11. In thread control mechanism for the weft ends of a weft replenishing loom, a pneumatic thread holder for said weft ends, a hollow thread collector communicating pneumatically with and extending downwardly from said thread holder, 25 a porous tube within which subatmospheric pressures exist extending upwardly from the bottom of the collector within the latter and terminating below the thread holder, and a door on the collector between the top and bottom thereof 30 adjacent to the upper end of said porous tube.

12. In thread control mechanism for the weft ends of a weft replenishing loom, a pneumatic thread holder for said weft ends, a hollow cylindrical thread collector communicating pneumatically with and depending from the thread holder, 35 a porous tube in which subatmospheric pressures exist extending upwardly from the bottom of the collector within the latter and having its upper end terminating between the top and bottom of the collector, and a normally closed door on the collector which when open affords access to the interior of said collector at a point intermediate the top and bottom thereof adjacent to said upper end of said porous tube.

40 13. A thread collector for the weft ends of a weft replenishing loom having a pneumatic thread holder, said collector comprising a hollow cylindrical member one end of which is adapted for close fitting engagement with said 45 thread holder, a porous tube within which subatmospheric pressures can be created extending into the other end of said cylindrical member and having one end thereof terminating between the ends of said member, and a door opening into the cylindrical member intermediate the ends thereof adjacent to said one end of said porous tube.
